FIG. 1 is a top plan view of a package of bottles; showing my new design with the cover omitted;

FIG. 2 is a perspective view thereof, shown side by side with the removed cover;

FIG. 3 is a top plan view similar to FIG. 1 showing a modified form of my new design;

FIG. 4 is another top plan view similar to FIG. 1 but showing still another modified form of my new design;

FIG. 5 is a perspective view of the design shown in FIG. 1 with the cover in place;

FIG. 6 is a perspective view of the design shown in FIG. 3 with the cover in place; and

FIG. 7 is a perspective view of the design shown in FIG. 4 with the cover in place.

The vertical lines around the center of the containers in FIGS. 5, 6, and 7, indicate the color contrast of a tape holding the cover and bottom portions together.

I claim:

The ornamental design for a package of bottles, substantially as shown and described.
